ATTORNEYS

UNITED STATES PATENT OFFICE.

JACOB STEIN, OF NEW YORK, N. Y.

NETHER GARMENT.

Application filed April 17, 1920. Serial No. 374,622.

To all whom it may concern:

Be it known that I, JACOB STEIN, a citizen of the United States, and a resident of the city of New York, in the borough of 5 Manhattan and county and State of New York, have invented a new and Improved Nether Garment, of which the following is a full, clear, and exact description.

This invention relates to garment protectors for children and has particular reference to an improvement in nether garments or diaper covers.

While some protectors of this character are now in use which shield the lower clothing, no provision has ever been made for the protection of the upper garments from dampness when the child is in a lying posture.

It is therefore one of the primary objects 20 of the present invention to construct a nether garment of the character described in which provision is made for protecting and shielding the upper clothing of the wearer.

Another object of the present invention 25 is to provide in combination with the diaper protector, means for protecting the upper clothing of the wearer and in which said means also functions as a supporter for the diaper cover.

A further object of the present invention 30 is to provide a garment of the character described which is simple in construction, inexpensive to manufacture and which is strong, durable and efficient for the purpose 35 for which it is intended.

With these and other objects in view, some of which will be more apparent hereafter, reference is made to the following 40 description, claims and accompanying drawings, in which

Figure 1 is a perspective view of the garment illustrating the application of the same.

Figure 2 is a similar view of the garment 45 removed.

Figure 3 is a fragmentary perspective view of a slightly modified form of the invention.

Referring to the drawings by characters 50 of reference which denote like parts throughout the several views thereof, 10 designates a diaper cover of standard construction which is provided with the crotch flap 11 and the side flaps 12 which are secured to each other by buttons 13. The protective bib 14 which is secured to the rear

upper edge of the diaper cover or formed as an integral part thereof, is preferably constructed of rubberized cloth or fabric similar to the material from which the diaper cover proper is made. In the preferred embodiment of the invention the said bib is in the nature of an extension having a head receiving opening 15, the free extremity 16 thereof being adapted to lie over the chest 65 of the wearer, the material defining the sides of the openings constituting shoulder straps 17, as clearly illustrated in Figure 1 of the drawings. The extremity 16 has secured thereto a pair of elastic straps 18, 70 the free ends of which are secured to a tab 19 provided with a button hole 20, adapted to button over the upper button 13 of the diaper cover to maintain the bib 14 in place and support the front of the diaper cover. 75 By this arrangement it will be obvious that when the child is in a lying posture, dampness which overflows the diaper cover will be prevented from penetrating and reaching the upper portion of the outside clothing at 80 the back thereof. It will be also observed that the bib and the tab attached thereto by the elastic straps serves as a perfect support for the diaper cover.

In the modified form illustrated in Figure 85 3 of the drawings, the free extremity 16 is provided with side straps 21 which button as at 22 to the rear side edges of the bib 14 and which underlie the arms to provide an additional means for retaining the edges 90 of the bib 14 in operative contact with the body of the wearer to prevent leakage.

While there has been illustrated and described several preferred embodiments of the invention, it is understood that no limitation is necessarily made to the precise details 95 of construction as changes and alterations which are covered by the appended claims may be resorted to when found expedient.

Having thus described my invention, what, 100 I claim as new and desire to secure by Letters Patent, is:

1. The combination with a diaper cover, of an extension secured medially of the rear upper edge of said diaper cover constituting 105 a moisture proof bib adapted to protect the rear upper portion of the clothing of the child when in lying posture, and a pair of elastic straps for connecting the front upper edge of the diaper cover to the free end of said 110 extension to retain the extension in proper position.

2. In a child's garment, the combination with a diaper cover, of a moisture proof extension constituting a protective bib for the rear upper clothing of the child, said extension being secured medially to the rear upper edge of the diaper cover, and a pair of straps for connecting the front upper edge of the diaper cover with the free end of said extension, said extension being adapted to be supported by the shoulders of the child.

3. In a child's garment, the combination with a diaper cover, of a moisture proof bib secured medially to the rear upper edge thereof, said bib having a head receiving opening, and straps provided at the free end of said bib adapted for connection with the upper front edge of the diaper cover to re-

tain the bib in position and support the front of the diaper cover.

4. In a child's undergarment, the combination with a diaper cover having side flaps and a crotch flap having interengageable fastening elements for securing the side flaps together and the crotch flap to the side flaps, of a moisture proof bib secured medially to the rear upper edge of the diaper cover, said bib having a head receiving opening, and means carried by the free lower front edge of the bib adapted to be interengageably associated with the fastening elements for securing the side flaps of the diaper cover together whereby to provide a moisture protection to the outer garments of the child when in lying posture.

JACOB STEIN.
